CLAUDE S. SNODDY, HOMER A. HINES, AND HAMILTON ALVI MEGONIGLE, OF BARTLESVILLE, OKLAHOMA.

ATTACHMENT FOR PUMP PISTONS.

Application filed June 14, 1927. Serial No. 198,774.

This invention relates to valved pistons such as are commonly used in pumps employed in pumping oil and other drilled wells, and has more particular reference to 5 an improved attachment, for pistons of this kind, embodying means for automatically opening the piston valve when the same becomes "set" or "stuck", due to formation of a partial vacuum below said valve by reason 10 of an insufficient flow or supply of oil in the well, said means being adapted to open the piston valve by engagement with the standing valve of the pump upon the downstroke of the piston when the normal stroke of the 15 latter is changed and to automatically permit closing of the piston valve upon the upstroke of the piston.

It is a common occurrence for the piston valves of oil well pumps to become set or 20 stuck, and when such condition arises the pumping is necessarily discontinued. In some cases, even though a sufficient quantity of oil eventually flows into the well to resume pumping, the pressure of the oil in the 25 well is not sufficient to raise or open the piston valve, and it becomes necessary to remove the piston from the well to unseat the valve, an operation which is very troublesome and entails considerable expense and loss of time.

30 The primary object of the present invention, therefore, is to provide an improved means by which the above mentioned trouble, expense and loss of time is obviated, and which, by merely lengthening the piston rod 35 of the pump or the equivalent is brought into active relation to the standing valve for opening the piston valve on the downstroke of the piston, thereby relieving the partial vacuum below said piston valve and permitting 40 the pumping to be immediately resumed when the level of oil in the well again rises.

A further object is to provide a valve 45 opening device of the above kind which may be readily applied to the conventional type of pump pistons now in general use, and which is extremely simple and durable in construction as well as efficient in operation.

The invention consists in the novel form, combination and arrangement of parts here- 50 inafter more fully described, shown in the accompanying drawings and claimed.

In the drawings:

Figure 1 is a view showing a pump piston and standing valve in elevation within a well casing, the piston being provided with a 55 valve unseating device constructed in accordance with the present invention.

Figure 2 is a view somewhat similar to Figure 1 with the piston in section and lowered so that the piston valve is held unseated by the unseating device, the latter being engaged with the standing valve cage.

Figure 3 is a fragmentary sectional view showing the lower end of the piston and adjacent parts of the valve unseating device 65 shown in Figure 2, the parts being in the normal position of Figure 1 when disengaged from the standing valve.

Figure 4 is an enlarged section on line 4-4 of Figure 1.

Figure 5 is an enlarged section on line 5-5 of Figure 1, and

Figure 6 is an enlarged perspective view of the tubular guide for the valve unseating rod.

Referring more in detail to the drawings, 5 indicates the well or pump casing having the usual standing valve including a cage 6 and a movable valve member 7 therein. Reciprocable in the well casing 5 above the standing valve is the usual piston including a tubular body 8 on the upper end of which is secured the cage 9 of the movable piston valve member or ball 10 which seats by gravity upon the seat 11, the cage 9 having the 85 usual stem 12 for connection with the pump rod 13. The piston body 8 has the usual reduced lower end portion upon which are mounted the ordinary packing cups 14 and spacers 15, and the lower end of the said piston body is externally threaded to ordinarily receive nuts to secure the packing cups and spacers in place.

In accordance with the present invention a tubular casing 16 is threaded onto the lower end of the piston body 8, and this casing 16 is formed intermediate its ends with an internal annular flange 17 in which is slidably fitted a tubular guide member 18 which, in turn, is fitted on the lower end portion of a valve unseating or lifting rod 19 that has a threaded lower end or terminal 20

projecting below the guide member 18. The lower end of the guide member 18 is threaded, as at 21, and threaded onto the lower ends of the guide member 18 and rod 19 is a nut member 22 which has a reduced upper end portion 23 slidably fitting and engaged in the lower end of the casing 16. Surrounding the guide member 18 within the casing 16 and between the flange 17 and the upper end 10 of the nut member 22 is a helical compression spring 24 which normally lowers the rod 19 so that its upper end is below the seat 11 of the piston valve 10, downward movement of the rod 19 being limited by means of a head 15 25 on the upper end of the guide member 18 adapted to seat upon the flange 17 before the reduced upper end of the nut member 22 can move out of the lower end of casing 16. The casing 16 is of lesser diameter than the well 20 casing and entirely spaced from the latter to permit free passage of the oil, and such oil is allowed to enter the piston body 8 by providing the casing 16 with a circular series of horizontally aligned and uniformly spaced 25 openings 26 at a point above the flange 17 and below the internal threads in the upper end of said casing 16.

In assembling the device, the guide member 18 is placed in the casing 16 and the 30 spring 24 is then placed on the member 18 and within the casing 16 below the shoulder 17. The head 25 is formed with a screw driver kerf 27, and by means thereof the member 18 is then threaded into the nut member 22 which is placed at the lower end 35 of spring 24. The rod 19 is then inserted in the member 18 and threaded into the nut member 22, whereupon, the rod 19 is inserted in the lower end of the piston body 8 and 40 casing 16 is threaded onto the lower end of the latter.

In operation, the piston is set in the well casing so that a space is left between the nut member 22 and the top of the standing valve 45 cage when the piston is at the downward limit of its normal stroke. Under this condition the piston is worked until its valve 10 becomes set or stuck. When this occurs, the piston is suitably lowered beyond the 50 limit of its normal downstroke until the nut member 22 engages the top of the standing valve cage 6 and the spring 24 is compressed sufficiently to permit the rod 19 to move upwardly and raise or unseat the valve 10, 55 thereby breaking the partial vacuum beneath the latter and insuring opening of the same when the level of the oil in the well again rises. As soon as the piston is again raised the spring will return the rod 19 and 60 associated parts to normal position so that the piston valve will function properly when the pumping is resumed.

It will thus be seen that the present device will obviate the necessity of removing the

piston from the well, and that the same may 65 be readily applied to pistons now in use. It will be further seen that the construction is exceedingly compact, simple and durable and provides efficient guiding and supporting means for the valve unseating 70 rod.

Minor changes may be made without departing from the spirit and scope of the invention as claimed.

What we claim as new is:

1. In a well pump, the combination with 75 a valved piston, of a rod located in the piston below its valve and projecting below the piston, an apertured casing attached to the lower end of the piston through which said rod slidably projects, said rod being guided in said casing and being adapted to be thrust upward to open the piston valve when the normal stroke of the piston is changed, a tubular guide member slidably fitted in the 80 casing and on the lower end of said rod, and a nut member secured on the lower ends of 85 said guide member and said rod.

2. In a well pump, the combination with 90 a valved piston, of a rod located in the piston below its valve and projecting below the piston, an apertured casing attached to the lower end of the piston through which said rod slidably projects, said rod being guided in said casing and being adapted to be thrust 95 upward to open the piston valve when the normal stroke of the piston is changed, a tubular guide member slidably fitted in the casing and on the lower end of said rod, a nut member secured on the lower ends of 100 said guide member and said rod, an internal annular flange on the casing, and a head on the upper end of said guide member adapted to seat on said flange to limit the downward movement of said rod.

3. In a well pump, the combination with 105 a valved piston, of a rod located in the piston below its valve and projecting below the piston, an apertured casing attached to the lower end of the piston through which said rod slidably projects, said rod being guided in said casing and being adapted to be thrust 110 upward to open the piston valve when the normal stroke of the piston is changed, a tubular guide member slidably fitted in the 115 casing and on the lower end of said rod, a nut member secured on the lower ends of said guide member and said rod, an internal annular flange on the casing, and a spring encircling the guide member between said 120 flange and the nut member for normally lowering the rod below the seat of the piston valve.

4. In a well pump, the combination with 125 a valved piston, of a rod located in the piston below its valve and projecting below the piston, an apertured casing attached to the lower end of the piston through which said

rod slidably projects, said rod being guided in said casing and being adapted to be thrust upward to open the piston valve when the normal stroke of the piston is changed, a tubular guide member slidably fitted in the casing and on the lower end of said rod, a nut member secured on the lower ends of said guide member and said rod, the

upper end of said nut member slidably fitting in the lower end of said casing. 10

In testimony whereof we affix our signatures.

CLAUDE S. SNODDY.
